A. H. BROWN.
BRICK PRESS.

No. 11,658.

Patented Sept. 5, 1854.

UNITED STATES PATENT OFFICE.

ALEXANDER H. BROWN, OF GEORGETOWN, DISTRICT OF COLUMBIA.

BRICK-PRESS.

Specification of Letters Patent No. 11,658, dated September 5, 1854.

To all whom it may concern:

Be it known that I, ALEXANDER H. BROWN, of the city of Georgetown and District of Columbia, have invented a new and useful

5 Machine for Manufacturing Bricks from Dry Clay; and I do declare that the following is a full, clear, and exact description of the construction and operation of the same, reference being had to the annexed drawings, making a part of this specification, in which—

10 Figure 1 is a vertical side view. Fig. 2 a sectional view through line *a b*, Fig. 1. Fig. 3 a front view, and Fig. 4 a birdseye view or 15 plan. Fig. 5 a plan of the mold, Fig. 6 an end elevation of the same. Fig. 7 an isometric view.

15 Like letters representing like parts in the different figures, the whole being laid down 20 to a scale of two inches to the foot except Figs. 5 and 6, which are four inches to the foot, in order that any one skilled in the art of machinery may construct a machine 25 from the accompanying drafts of the Letters Patent.

A, A, A, Fig. 1, represents the frame in three separate portions consisting of the top, side and bed pieces securely fastened by six bolts on each side, four of which reach 30 through from the bed piece at Z, Z, Z, Z, to the top of the frame, thus tying the whole securely together.

B, B, is a chain of molds of a peculiar form revolving over the octagonal wheels 35 C, C. This chain of molds is constructed as follows: Three sides of a rectangular frame or box of iron are cast without a bottom and one side, as shown in Figs. 5, 6, and 7. This frame forms three sides of the mold in 40 front and at the lower part of the side *a* Figs. 5 and 7 there is placed a projecting plate of iron *c*, Figs. 5 and 7. The three sides *a* and *b* and the projecting plate *c* forming a solid casting.

45 Attached to the projecting plate *c* as well as to the side B, are two half circular lugs D, D, which serve the double purpose of connecting the molds together and forming teeth gearing into the octagons C, C, Fig. 1, 50 by which the chain is caused to revolve. As the chain revolves upon the octagons, the projecting plate *c*, Fig. 5, plays within the hollow square, when by the movement of the octagon the chain forms a horizontal line, 55 the projecting plate *c* takes its position and forms the bottom of the mold; the front of

the side of one frame closes against the ends of the sides *b*, *b*, of the preceding frame and forms a perfect rectangular mold, when it is ready to receive the clay from the hopper 60 above it.

I can vary the form of the molds by dispensing with either ends *b* *b* or the bottoms *c*, *c*, and perform the compression immediately upon the compression plate T, and 65 sides guides. In these cases the molds would be connected together by outside links. Two of the octagonal wheels are placed on the front of the machine, these serve to raise and bring the molds into a horizontal line 70 preparatory to their receiving the pulverized clay; the other two serving to open the molds at the back end of the machine in order to enable the offbearer to receive the 75 bricks after being compressed or to deliver them upon an endless apron to be conveyed to any convenient point.

D is a hopper through which the clay passes into the molds.

E is a first plunger which compresses the 80 clay to within one and one half inches of the thickness of the finished size of the brick, when the second plunger F, finishes the brick by a plunge of one and one half inches; both plungers acting simultaneously. 85 Two bricks remain partially compressed between the first and second plungers.

G is a scraper placed between the first and second plungers in a diagonal position in 90 order to throw off any clay that may rise above the divisions of the molds before they arrive at the second plunger F, the scraper lies even with the frame immediately below the letter G, and cannot be shown. This, however, I do not consider important.

H, is a ratchet wheel keyed upon the shaft of the front octagon in order to propel the chain of molds B, B, at each thrust of the ratchet bar K. This movement is produced by each revolution of the tooth wheel L, acting upon said bar which acts upon the ratchet stock O, and pall hand I, the mold remaining stationary while the pall hand is returning to take hold of the ratchet tooth at which time the plungers descend and produce the required compression.

L, L' are two tooth wheels upon whose shafts are placed the two cams M and N which actuate the two plungers E and F, in the downward motion and are shown in 110 Figs. 2, 3, and 4.

P, P, P, P, P, P, P, P, are eight of sixteen

guides fastened to the plungers, eight above and eight below (Figs. 1, 2, and 3) through which pass eight turned rods or bars W, W, giving direction to the two plungers E and 5 F.

Q, Q, Q, Q, Figs. 1 and 4, are four of eight set screws for the purpose of tightening the chain of molds B, B, after being linked together.

10 R, Figs. 1, 2, 3, 4, is a driving pulley. S, Figs. 1, 2, 3, 4, is a fly wheel.

T, T, Fig. 2 are two compress plates upon which the mold rests while the bricks are being compressed.

15 U, Figs. 1, 3, 4 is a small pinion upon the driving pulley shaft, gearing into the two tooth wheels L, L, and giving motion to all the different parts of the machine.

V, V, V V Figs. 1, 2 are eight spiral springs 20 which cause the plungers E, and F, to react as soon as they are disengaged from the two cams in order to let the succeeding molds take their places upon compress plates T, T.

W, W, W, W, Figs. 1, 2 are four of eight 25 bolts or bars extending from Z, Z, Z, Z, Fig. 1 entirely through from bottom to top of frame in order to make the frame secure as well as to receive the whole force of compression and to relieve the castings from any 30 strain. That portion of these bolts W, W, W, W, encircled by the spiral springs, being turned smooth and true for the purpose of producing an undeviating thrust of the plungers into the molds through the guides 35 P, P, P, P, Figs. 1, 2.

X, X, Figs. 1, 2, are two bolts passing through from side to side of the frame and secured by heavy nuts and placed immediately below the compress plates to prevent 40 any lateral yielding during compression.

Y, Y, Y, Y, Figs. 1, 2 are four hollow columns on each side of frame through which the rods W, W, W, W, pass to receive the nuts Z, Z, Z, Z, Figs. 1, 2.

45 The mode of operation and peculiar advantages of my machine are as follows: When power is communicated from the driving pinion U through machinery above described to the octagons C, C, as the octagons revolve they propel the chain of molds. By the arrangements I have described the movement of molds is made progressive but not continuous; they stop just long enough to receive the two plungers 50 which act simultaneously. The molds are charged by passing under the hopper which is kept filled with clay, the first plunger descending upon the clay gives to it only a partial compression within the mold; when 55 the mold arrives beneath the second plunger it stops just long enough for the clay to receive its final compression; the second

plunger giving a more powerful compression from the fact that the radius of the cam which operates it is smaller than that of the 65 cam operating the first plunger. By using two plungers acting as above I am enabled to effect what I could not with one plunger, using the same power. The bricks thus made are delivered by the molds opening as 70 they revolve over the back octagon; a great advantage of this mode of discharging the bricks from the molds is that while the surface then is equal to that of the best front brick, the smoothness and glossiness of surface, preventing the adhesion of mortar, produced by forcing the bricks upward from the mold after being pressed is avoided.

The driving pulley of my machine is calculated to revolve at a speed of two hundred 80 revolutions per minute which produces fifty plunges in the same space of time and consequently fifty bricks per minute are produced.

What I claim as my invention and desire 85 to secure by Letters Patent is,—

1. I do not claim the broad device of constructing molds which close before receiving the clay and open when discharging the 90 bricks but do claim the peculiar construction 95 of my molds, as described and shown, for this purpose, each separate frame or link in the chain of molds forming a part of two molds, the projecting plate c, as the molds pass over the first octagon C' closing so as to form the bottom of the preceding frame and the side a closing against the ends b b of the preceding frame so as to form a perfect mold when the chain is horizontal; as the frames pass over the second octagon C'' the 100 sides a and the ends b b releasing themselves from the plate c of the preceding frame leaving the brick free upon the plate c so that it may be easily discharged, the lugs d 105 gearing into the octagons for propelling the molds.

2. I claim for the purpose of compressing dry clay into bricks the combination of the two plungers E and F with the cams M and N, the cams revolving and the plungers moving in unison, the first cam M, having the longest radius and causing the first plunger E to descend the greatest distance upon the easily compressible clay; the second cam N which actuates the plunger F 115 having a smaller radius than the first cam M, so that the greatest force of compression is applied to the clay already partially compressed where the greatest power is required.

A. H. BROWN.
